CONTROLLING APPARATUS

Rex D. McDill, East Cleveland, Ohio, assignor to
Adjustable Scaffold & Form Company, Cleve-
land, Ohio, a corporation

Application September 2, 1932, Serial No. 631,529

13 Claims. (Cl. 192—01)

This invention relates to controlling apparatus and is particularly applicable to the control, from a distant point, of an engine or the like.

An object of the invention is to provide improved controlling means by which an engine or like source of power can be started and stopped from a remote point.

Another object is to provide an improved controlling means by which, from a remote point, apparatus may be connected with and disconnected from a source of power.

Another object is to provide an improved controlling means by which the power or speed of an engine or similar device may be controlled from a remote point.

Other objects will hereinafter appear.

The invention will be better understood from the description of one practical embodiment thereof illustrated in the accompanying drawing in which:

Figure 1 is a diagrammatic representation of the controlling means as it may be applied to an internal combustion engine.

Figure 2 is a fragmentary view of the motors F and R applied to a single jaw clutch of conventional type, and

Figure 3 is a similar fragmentary view showing the motors F and R applied to a conventional reversing jaw clutch.

In Figure 1, the engine itself is not illustrated, but it will be understood that this is of any well known or desired construction, such as a gas, gasoline, or oil engine, the throttle being controlled by an arm T, the explosive charges being electrically ignited by the ignition circuit I which has interposed in it a switch S, and that the engine is also equipped with a choke controlled by a lever C to insure a rich mixture during starting.

The engine is also provided with an electrical starting motor in the usual manner.

A clutch is provided for connecting the motor to any mechanism to be driven thereby, and may be conveniently operated by clutch operating apparatus such as described in my copending application Serial Number 629,816, filed August 22, 1932, now Patent No. 1,990,048, issued February 5, 1935. For this purpose, two electric motors are shown, one of which, F, may be used to throw the clutch into a position for driving the mechanism in a forward direction, and the other, R, may move it to position for driving in a reverse direction. If desired, one motor may be used to throw the clutch into engagement by moving it in one direction, and the other to dis-

engage the clutch by moving in the other direction. It will be understood that in such an installation the clutch may be of the well known type of reversing clutch such as is used in motor boats and other marine installations, or the like, or it may be of the type used in automotive land vehicles which merely engages and disengages, and which type is likewise well known to those skilled in the art.

In Figure 1 of the drawing are shown a plurality of button-operated switches 2, 3, 4, 5, and 6 and also a switch 7 having a pivoted arm. One side of each of these switches is connected to a conductor 8 which extends from a source of current 9, conveniently a battery of relatively high voltage and low amperage such, for instance, as a 90 volt "B" battery of the kind provided for use in radio sets.

From the opposite sides of switches 2 to 6, conductors 10 to 14 extend to the magnet coils 15 to 19 respectively. The opposite ends of the coils of the relays 15 to 17 are connected to a conductor 20 which returns to the battery 9, while the opposite ends of relays 18 and 19 are connected to a conductor 21 which is connected to a thermostatic switch 22. From this switch a conductor 23 extends to the conductor 20 above mentioned. This switch is positioned in the cooling system of the engine or some similar place so that the clutch cannot be operated until the engine has been properly warmed up.

The switch 7 is provided with a plurality of contacts 24, connected by conductors 25 to spaced taps upon the magnet coil of a relay 26, one end of this coil being connected to the conductor 20.

The relays control a number of circuits which actuate the various parts of the engine control and which derive their power from sources of electricity 28a and 28, most conveniently storage batteries having a relatively high amperage and low voltage, these batteries being connected in series and grounded at one end, as indicated at 29.

From the other end of the battery 28a, conductor 30 extends having branches 31, 32, 33 and 34, the first of which terminates in a contact in relay 15 and is adapted, by means of this relay, to be connected to conductor 35 which actuates the mechanism for starting the motor. This conductor is connected to a solenoid 36, the other end of which is grounded, which solenoid is provided with an armature 37 connected to the throttle lever T. In parallel with the solenoid is a starting motor M which rotates the crank

shaft of the engine to start the same. Mechanically connected to the lever T is the spark control mechanism, so that when the solenoid 36 is actuated, the throttle is opened to the proper position for starting the engine, and the spark retarded to its starting position, and simultaneously the crankshaft of the engine is rotated by starting motor M. The lever T is provided with an arm terminating in a lug Ta which may engage the side of the controlling lever T' to mechanically and positively return the same to starting position when lever T is returned thereto.

Branch 33 is connected by relay 16 to a conductor 38 and so to a solenoid 39, the armature 40 of which is connected to the choke lever C. Hence, the starting of the engine may be accomplished by the actuation of buttons 2 and 3, the former controlling the ignition or spark and throttle as well as starting the motor, and the latter controlling the choke.

The operator can thus choke the engine as much or as little as he desires and can actuate the starting motor as long as may be necessary.

Branch conductor 34 is adapted to be connected by relay 17 to a conductor 41 which extends to a solenoid 42, grounded at its other end, as are the two above described, and having an armature 43 connected to one element of ignition switch S, so that when it is desired to stop the motor, it is only necessary to close the switch 4, interrupting the ignition circuit until the motor has ceased to turn.

A spring 44 is connected to lever T and may be sufficiently strong to move this lever to running position when switch 2 is released. This would be entirely satisfactory where it is desired to operate the engine only at a fixed throttle and spark setting.

A type of clutch which merely engages and disengages is illustrated in Figure 2, in which the shaft driven by the engine or other source of power is indicated at 101, the shaft which is to be driven being indicated at 102.

Shaft 101 has fixed to it one element 103 of a jaw clutch, while the other element of the jaw clutch conjugate thereto is slidably splined on the shaft 102.

Pivoted on a shaft 105 is an arm 106 by which the jaw member 104 may be slid along shaft 102 to become engaged with or disengaged from jaw 103, and fixed to this arm to rotate therewith is a toothed sector 107 with which meshes a gear 108 fixed to the shaft of motor F and also a gear 109 similarly fixed to the shaft of motor R.

It will be understood that, with the parts seen in Figure 2, when motor F is operated the sector 107 is swung to the left, moving the jaw 106 into locking engagement with jaw 108, and that when motor R is actuated, the sector is swung to the right, disengaging the jaws.

Similarly, Figure 3 illustrates a clutch mechanism for obtaining two directions of rotation of a driven shaft when operated from a drive shaft which rotates in a single direction.

The drive shaft is illustrated at 201 and the driven shaft at 202. To the former is fixed a bevelled pinion 203 and rotatable on the latter is a similar bevelled pinion 204, both pinions meshing with a gear 205, so that they rotate in opposite directions.

Pinion 203 has fixed to it an element 206 of conventional jaw clutch and pinion 204 has fixed to it similar clutch element 207.

Splined on shaft 202 is a double clutch element 208 arranged to be actuated by an arm 209

mounted on a pivot 210 and fixed to a toothed sector 211.

With this sector mesh pinions 212 are fixed to the shaft of motor F and 213 fixed to the shaft of motor R.

By the actuation of motor F, sector 211 is swung to the left, engaging elements 206 and 208, and therefore driving shaft 202 in the same direction as 201. When motor R is actuated, sector 211 is swung to the right so that clutch elements 207 and 208 are engaged and shaft 202 is driven through gears 203, 205, and 204 in the opposite direction to 201.

For situations in which a fixed setting is not desired the switch 7 is utilized and, by it, it will be seen that any desired length of coil 26 may be energized.

The plunger 27 of this relay may, therefore, be moved to any one of a plurality of positions, in each of which one side will bear upon contact 45, connected to conductor 32, and the other side will contact one of the elements 46. These elements are connected by conductors 47 to taps on solenoid 48, having an armature 49 supported by springs 50 and 51 and which is mechanically connected with the throttle controlling lever T'.

By this means, it will be seen that lever T' may be moved to any of a plurality of positions, each corresponding to one of the contacts 24, and that this lever will correspondingly open or close the throttle and, if it contacts lug Ta, advance or retard the spark of the engine.

From between batteries 28a and 28 a conductor 52 extends branching to contacts contiguous to relays 18 and 19, and by the actuation of either of these relays, it may be connected to conductors 53 or 54, through the former of which current may be supplied to motor F, which, as above described, throws the clutch into engagement for driving the mechanism in a forward direction, or with motor R which, as has likewise been explained, throws the clutch into rearward driving engagement. The clutch may conveniently be returned to neutral position by a spring or the like.

Alternatively, one motor may be used to throw the clutch in, and the other to throw it out, if there is no necessity for reversing the clutch action.

A generator G is connected to conductor 30 through a generator cut-out 55 and conductor 56, the other side of the generator being grounded, as shown. This generator is driven by the engine and serves to recharge batteries 28a and 28, from which a fairly large quantity of electricity may be drawn to actuate the devices.

It will be seen that the relays are actuated by a high voltage current having relatively low amperage, and that the devices actuated by the relays may all be positioned very close together adjacent the engine, so that only the relatively small high voltage currents need be transmitted across the space between control and engine, and that relatively light wiring may, therefore, be used.

While I have described the illustrated embodiment of my invention in some particularity, obviously many modifications thereon will readily occur to those skilled in the art to which this appertains, and I do not, therefore, limit myself to the precise details shown and described but claim as my invention all embodiments coming within the scope of the subjoined claims.

I claim:

1. Controlling mechanism for an internal com-

- bustion engine having a throttle and a starting motor, which comprises electro-magnetic means operatively connected to the throttle and arranged upon energization to move the throttle to the starting position, a circuit including said electro-magnetic means and said starting motor, a source of current supply in said circuit, and manually operable controlling means controlling the supply of said current to said circuit. 5
5. Controlling mechanism for use in conjunction with an internal combustion engine having a throttle and a starting motor, a control apparatus comprising a solenoid operatively connected to the throttle and arranged to move the same to starting position when energized, an electric circuit including the solenoid and motor, a source of electrical energy in said circuit, a switch in said circuit, and manually operable means controlling said switch. 10
10. 2. In combination with an internal combustion engine having a throttle and a starting motor, a control apparatus comprising a solenoid operatively connected to the throttle and arranged to move the same to starting position when energized, an electric circuit including the solenoid and motor, a source of electrical energy in said circuit, a switch in said circuit, and manually operable means controlling said switch. 15
15. 3. Controlling mechanism for use in conjunction with an internal combustion engine, which comprises electro-magnetic means associated with a control of said engine, a source of relatively low potential and relatively high current electrical energy, a circuit including said source and said electro-magnetic means, electrically actuated means controlling the circuit, a second circuit extending from said controlling means to a remote point, manually operable circuit controlling means in said second circuit at said remote point, and a source of relatively high potential and low current electrical energy in said second circuit. 20
20. 4. Controlling mechanism for use in conjunction with an internal combustion engine having a plurality of controls, which comprises a plurality of electro-magnetic means associated with said controls, a circuit including a source of relatively high current and low potential electricity and including each of said electro-magnetic means, a circuit breaker associated with each of said electro-magnetic means, an electrically actuated operating device connected with each circuit breaker, a control board at a point remote from said engine, a plurality of conductors extending from said operating devices to said control board, manually operable means controlling the operating devices associated with said conductors on said control board, said conductors and devices on the control board comprising a circuit and including a source of relatively high potential low current electricity. 25
25. 5. Controlling mechanism for use in conjunction with an internal combustion engine having a throttle, which comprises electro-magnetic means associated with the throttle of said engine, a source of relatively low potential and relatively high current electrical energy, a circuit including said source and said electro-magnetic means, electrically actuated means controlling the circuit, a second circuit extending from said controlling means to a remote point, manually operable circuit controlling means in said second circuit at said remote point, and a source of relatively high potential and low current electrical energy in said second circuit. 30
30. 6. Controlling mechanism for use in conjunction with an internal combustion engine having an ignition circuit, and a switch in said ignition circuit, which comprises electro-magnetic means associated with the switch of said engine, a source of relatively low potential and relatively high current electrical energy, a circuit including said source and said electro-magnetic means, electrically actuated means controlling the circuit, 35
35. 7. Controlling mechanism for use in conjunction with an internal combustion engine having a throttle and a timing mechanism, which comprises electro-magnetic means associated with the throttle and timing mechanism of said engine, a source of relatively low potential and relatively high current electrical energy, a circuit including said source and said electro-magnetic means, electrically actuated means controlling the circuit, a second circuit extending from said controlling means to a remote point, manually operable circuit controlling means in said second circuit at said remote point, and a source of relatively high potential and low current electrical energy in said second circuit. 40
40. 8. Controlling mechanism for use in conjunction with an internal combustion engine having a throttle and a timing mechanism, electro-magnetic means associated with said throttle, electro-magnetic means connected therewith associated with said timing mechanism, a source of relatively low potential and relatively high current electrical energy, a circuit including said source and said electro-magnetic means, electrically actuated means controlling the circuit, a second circuit extending from said controlling means to a remote point, manually operable circuit controlling means in said second circuit at said remote point, and a source of relatively high potential and low current electrical energy in said second circuit. 45
45. 9. Controlling mechanism for use in conjunction with an internal combustion engine having a starting motor, a throttle and a timing mechanism, electro-magnetic means associated with said throttle, electro-magnetic means connected therewith associated with said timing mechanism, the starting motor being connected to said electro-magnetic means, a source of relatively low potential and relatively high current electrical energy, a circuit including said source and said electro-magnetic means, electrically actuated means controlling the circuit, a second circuit extending from said controlling means to a remote point, manually operable circuit controlling means in said second circuit at said remote point, and a source of relatively high potential and low current electrical energy in said second circuit. 50
50. 10. Control mechanism for an internal combustion engine provided with a throttle, with an electrical ignition system including a timer, and with a starting motor, which comprises electro-magnetic means operatively connected with the throttle and arranged upon energization to move the throttle to starting position, a circuit including said electro-magnetic means and the starting motor and also including a source of electrical current, circuit making and breaking means in said circuit controlling the supply of current to both the electro-magnetic means and the motor, interconnecting means between the throttle and timer whereby both are moved to starting position when current is supplied to the electro-magnetic means, and resilient means associated with said throttle and arranged to move the throttle and timer to running position when the electro-magnetic means is de-energized. 55
55. 11. Control mechanism for an internal com- 75

- bustion engine provided with a throttle and with a starting motor, which comprises electro-magnetic means operatively connected with the throttle and arranged upon energization to move the throttle to starting position, a circuit including said electro-magnetic means and the starting motor and also including a source of electrical current, circuit making and breaking means in said circuit controlling the supply of current to both the electro-magnetic means and the motor, and resilient means associated with said throttle and arranged to move the throttle to running position when the electro-magnetic means is de-energized.
12. Control mechanism for an internal combustion engine provided with a throttle and with a starting motor, which comprises electro-magnetic means operatively connected with the throttle and arranged upon energization to move the throttle to starting position, a circuit including said electro-magnetic means and the starting motor and also including a source of electrical current, circuit making and breaking means in said circuit controlling the supply of current to

both the electro-magnetic means and the motor, resilient means associated with said throttle and arranged to move the throttle to running position when the electro-magnetic means is de-energized, electro-magnetic operating means arranged to operate said circuit closer, and manually operable controlling means electrically connected therewith and situated at a remote point.

13. Controlling mechanism for use in conjunction with an internal combustion engine having a clutch, which comprises electro-magnetic means associated with the clutch of said engine, a source of relatively low potential and relatively high current electrical energy, a circuit including said source and said electro-magnetic means, electrically actuated means controlling the circuit, a second circuit extending from said controlling means to a remote point, manually operable circuit controlling means in said second circuit at said remote point, and a source of relatively high potential and low current electrical energy in said second circuit.

R. D. McDILL.
